UNITED STATES PATENT OFFICE.

RENÉ-MAX VALABRÈGUE, OF PARIS, FRANCE, ASSIGNOR TO LE RASOIR APOLLO, OF PARIS, FRANCE.

SAFETY RAZOR.

Application filed January 7, 1925, Serial No. 1,006, and in France December 2, 1924.

The present invention relates to safety razors of the type comprising a holder which is provided with a toothed guard and is adapted for receiving a thin razor blade having one or two cutting edges. The said blade is positioned either by lugs or pins provided upon the said holder and co-operating with suitable cut-out parts of the blade, or by clamping means combined with stop pieces whereby the position of the cutting edge is properly adjusted with reference to the said toothed guard.

In the known types of safety razor, the blade may be placed in its holder with either side outward, since the upper and lower faces of the said blade are identical.

Each time the razor is used for shaving, the cutting edge of the blade is upturned or bent back by reason of the resistance offered by the hair of the face. When the blade is sharpened by honing or stropping or by these two means combined, either by hand or in an apparatus, this will straighten out the bent edge or edges of the blade and will bring the same into the initial position i. e. into the plane of the blade.

If the blade thus sharpened is disposed in its holder in the inverted position, i. e. with the face which was previously at the top now turned downwards and inversely, when the blade is again used for shaving, the cutting edge or edges will be again upturned or bent back as above mentioned, but in this event this action will take place in the contrary direction.

Since the blade is upturned with reference to its holder at each operation of shaving, the cutting edge which is thus alternately bent towards each face of the blade will become rapidly broken, inasmuch as the metal is hardened by the great molecular strains to which it is subjected; this action is analogous to what takes place upon bending a piece of iron wire alternately to one side and the other, precisely in order to break it. In the case of the thin blade of a safety razor, the rupture of the cutting edge will give this part an irregular form, and this cannot be remedied by sharpening, so that the razor blade will be put out of use within a relatively short time.

In order to increase the life of the blade, suitable means are employed according to the present invention whereby the cutting edge shall always be turned back by the hair of

the face towards a given face of the said blade; in the following description, this face will be designated as the "lower face" of the blade. For this purpose, the blade must be disposed in its holder with a certain face invariably turned towards a given side of the said holder, and in this event the angle formed by the two limiting positions of the very thin metal forming the cutting edge will be substantially one-half the angle corresponding to the case in which the edge is alternately bent towards one face and the other. This will greatly reduce the strains and the consequent hardening of the metal, and the risk of breakage of the cutting edge will be reduced to a corresponding degree, while the life of the blade is increased correspondingly.

In order that the lower face of the blade shall invariably occupy the same position with respect to the holder, the said blade is constructed, according to the invention, in such manner that each face will be non-symmetrical with reference to any axis of symmetry of the blade or otherwise stated, that the two faces will be unlike. The said blades according to the invention, when double-edged, will be preferably made symmetrical with respect to their centre of figure so that the positions of the two cutting edges can be inverted with reference to the holder; this latter is also constructed in such manner that the blade can only occupy the proper position for securing it in the holder when the lower face of the blade is turned towards a given side of the holder which has been determined in advance.

In one embodiment of the invention, the razor blades have formed therein suitable perforations or notches which have the non-symmetrical position relatively to any axis of symmetry of the blade, whilst the holder is provided with studs whose shape and disposition correspond to those of the said cut out parts in the blade.

Should the razor blades be already formed with the usual cut out portions (perforations or notches) for use with ordinary holders, the said cut-out parts will be completed by further non-symmetrical cut out parts as above explained, said latter cut out parts forming part of the said usual cut-out portions or being separate therefrom. In this manner the improved blades according to the invention can be disposed in the known types

of holder which are not provided with the non-symmetrical positioning lugs or pins, as well as in the improved holders which are provided with the latter.

5 The constructional arrangements whereby the object of the said invention is attained, i. e. the prevention of inverting the blade with respect to its holder, may be completed by the use of suitable characters provided upon the 10 blades in order that one face may be readily distinguished from the other.

The appended drawings which are given by way of example show various embodiments of the invention.

15 Fig. 1 is a side view of an improved safety razor according to the invention.

Fig. 2 is a corresponding end view on the side of the handle.

20 Fig. 3 shows a thin razor blade with two curved cutting edges and provided with non-symmetrical notches.

Fig. 4 shows a thin razor blade with two curved cutting edges and provided with non-symmetrical perforations.

25 Fig. 5 shows a thin razor blade with two curved cutting edges and provided with non-symmetrical notches which enable the said blade to be employed with a holder having symmetrical positioning pins.

30 Fig. 6 shows a thin razor blade with two straight cutting edges and provided with non-symmetrical perforations.

Fig. 7 shows a thin razor blade with two straight cutting edges and non-symmetrical 35 perforations, these latter comprising symmetrical portions enabling the said blade to be employed with a holder having symmetrical positioning pins.

Fig. 8 shows a thin razor blade comprising 40 a single straight cutting edge and having a lateral notch, and

Fig. 9 is a corresponding side view.

In Figs. 3 to 8 the studs engaging in the cut out parts of the blades are shown in hatched 45 lines for the sake of clearness.

The safety razor of the known type which is shown in Figs. 1 and 2 comprises in the usual manner a handle 1, a comb shaped guard plate 2 which is optionally integral with the 50 said handle, and a cap or backing 3; the latter is provided with an axial screwthreaded shank, not shown, which is screwed into the said handle. The razor blade 4, shown in Fig. 3, is clamped between the said guard and 55 the backing.

At each side of the said backing is provided a stud 5 or 6 co-operating with a recess, or notch in the said guard in order that these two members will be correctly matched. The 60 said razor blade is apertured at the centre, at 7, for the insertion of the said shank of the backing, and is suitably notched at the edges to co-operate with the studs 5 and 6.

65 It is observed in Figs. 1 to 3 that the said studs are not disposed upon the backing 3,

nor are the notches in the razor blade formed upon the latter, in a symmetrical position relatively to any axis of symmetry of the said backing or of the razor blade, so that in these conditions the said blade cannot be turned 70 about with its faces in inverted positions and that when placing the blade in the holder, the user will be obliged to dispose the lower face of the blade in contact with the backing.

The studs 5 and 6 are symmetrically disposed relatively to the axis of the razor, and the notches in the blade 4 have a like position with respect to the geometrical centre of the said blade; so that the said blade can be given a 180° rotation on its centre and in the same 80 plane, whereby the position of the cutting edges will be inverted in relation to the backing.

Fig. 4 shows in the same manner as Fig. 3 a thin razor blade with two curved cutting 85 edges, the said blade 8 has therein two perforations which in this example are supposed to be circular and in which are engaged the round positioning pins 9 and 10 of a suitable safety razor holder which is suitably constructed to this effect. The said perforations serve the same purpose as the notches in the blade 4 indicated in the preceding figures, and are in like manner symmetrical with respect to the centre of figure of the blade. 90

Fig. 5 is a modification of Fig. 3 in which the razor blade 11 comprises two notches 12 and 13 which are non-symmetrical with reference to any axis of symmetry of the blade but are symmetrical with reference to the centre of figure of the said blade. The said notches comprise portions which are symmetrical with respect to the transverse axis $x-y$ of the said blade, so that the blade may be disposed in the holder of a known type of safety razor comprising symmetrical positioning pins 14 and 15. 95

Figs. 6 and 7 relate to the respective thin razor blades 16 and 19 having two straight cutting edges. The blade 16 has therein non-symmetrical perforations for the insertion of the studs 17, 18 which are likewise non-symmetrical with reference to the razor holder. The blade 19 has perforations which are also non-symmetrical but comprise portions which are symmetrical relatively to the transverse axis $z-t$ of the said blade, and due to the said symmetrical portions the blade can be mounted in a safety razor holder of a known type comprising symmetrical positioning pins. In Fig. 7, the numerals 20 and 21 indicate the non-symmetrical studs of the improved safety razor holder according to the invention. 110

The blade 22, Figs. 8 and 9, which is 115 mounted in its support 23 has but a single cutting edge; a notch is formed on one side adjacent the cutting edge, said notch being adapted for the insertion of the stud 24 of the improved safety razor holder. The said 120

130

blade may without inconvenience be employed with the holder of a safety razor of the usual type.

Obviously, the said invention is not limited 5 to the constructional forms hereinbefore described and illustrated in the drawings, these being given solely by way of example.

Having now described my invention, what I claim as new and desire to secure by Letters 10 Patent is:

1. In a safety razor, the combination with a holder having two axes of symmetry at right angle to each other and positioning studs asymmetrically arranged with regard 15 to said axes, of a blade having corresponding asymmetrical cut-out portions cooperating with said studs and also symmetrical cut-out portions.

2. In a safety razor the combination of a 20 holder, the flat blade engaging surface of which has two axes of symmetry at right angles to each other, said holder having positioning studs asymmetrically disposed thereon with respect to said axis, a blade having 25 corresponding axes of symmetry at right angles to each other and having corresponding apertures asymmetrically located with

respect to the blade axes and adapted to cooperate with said studs, said blade apertures being so asymmetrically disposed that the 30 corresponding axes of symmetry of the blade and holder will coincide with each other only when one given face of the blade engages the face of the holder.

3. In a safety razor according to claim 2, 35 said blade also having symmetrically arranged cut out portions one adjacent to each of said asymmetrically disposed apertures and communicating therewith.

4. In a safety razor according to claim 2, 40 said blade apertures being of non-circular form such that the blade can only be placed in position on the said asymmetrically disposed studs with a certain predetermined face thereof in contact with the holder, it being impossible 45 to register the apertures with the said studs with the blade inverted.

5. In a safety razor according to claim 2 said blade apertures having no common axis 50 of symmetry.

In testimony whereof I have signed my name to this specification.

RENÉ-MAX VALABRÈGUE.
